Primary Examiner — Lauren D McVey

(57) **CLAIM**

The ornamental design for a multifunction printer as shown and described.

DESCRIPTION

2.1 Perspective

2.2 Front

2.3 Rear

2.4 Left

2.5 Right

2.6 Top

2.7 Detail view of the encircled portion on reproduction **2.1**

2.8 Detail view of the encircled portion on reproduction **2.2**

2.9 Detail view of the encircled portion on reproduction **2.4**

2.10 Detail view of the encircled portion on reproduction **2.5**

2.11 Detail view of the encircled portion on reproduction **2.6**

The evenly spaced broken lines immediately adjacent to the claim depict the bounds of the claimed design, while all other evenly spaced broken lines are directed to environment. The dash-dot broken line that encircles a portion of each of reproductions **2.1**, **2.2**, **2.4**, **2.5**, and **2.6** and that surrounds the detail view on each of reproductions **2.7**, **2.8**, **2.9**, **2.10**, and **2.11** forms no part of the claimed design. The broken lines form no part of the claimed design.

1 Claim, 11 Drawing Sheets
